UNITED STATES PATENT OFFICE.

JAKOB SCHMOLINER, OF CHICAGO, ILLINOIS.

MOP-WRINGER.

Specification of Letters Patent. Patented Nov. 30, 1915.

1,162,403.

Application filed February 8, 1915. Serial No. 6,840.

To all whom it may concern:

Be it known that I, JAKOB SCHMOLINER, a subject of the Emperor of Austria-Hungary, and a resident of the city of Chicago, county of Cook, and State of Illinois, have invented certain new and useful Improvements in Mop-Wringers, of which the following is a specification.

My invention relates to improvements in 10 mop wringers, and has for its object the production of a device of this character which will be of improved construction and efficient in operation.

A further object is the production of a 15 mop wringer adapted for attachment to an ordinary pail, and which will be so designed as to adapt the same for adjustment to pails of different sizes, and which will be adapted for ready and expeditious attachment or detachment.

Other objects will appear hereinafter.

With these objects in view the invention consists in the combinations and arrangements of parts hereinafter described and 25 claimed.

The invention will be best understood by reference to the accompanying drawing forming a part of this specification, and in which—

30 Figure 1 is a perspective view of a mop wringer embodying my invention, the same being shown applied to a pail, Fig. 2 is a side elevation of the construction shown in Fig. 1, Fig. 3 is a top plan view of the construction shown in Fig. 1, and Fig. 4 is a detail front elevation of one end of the band which is adapted to embrace the pail in conjunction with which the device is employed.

35 The preferred form of construction, as 40 illustrated in the accompanying drawing, comprises a metallic band 1 which is adapted to embrace a conventional pail 2, as shown. The band 1 is provided at one end with an end piece 3 having key-hole slots 4 45 therein for releasable engagement with headed studs 5 projecting from said end of said band, as clearly shown in Fig. 4. A plurality of slots 4 is provided in the end piece 3 for engagement with the studs 5 in order to adapt said end piece for longitudinal adjustment upon the band 1 so as to permit of the device being used upon pails of various sizes. The ends of the band are 50 connected together by means of a bolt 6 55 which projects through the outwardly turned

perforated end of the end piece 3 and which engages with a slot 7 provided in the outwardly turned adjacent end of the band, as clearly shown in the several views. A thumb nut 6' coöperates with the bolt 6 in connecting the ends of the band, as will be readily understood.

Arising from opposite sides of the band 1 are supporting members 8 rigidly secured at their lower ends to said band. Rotatably mounted between the upper ends of the members 8 is a roller 9. Rigidly secured to and projecting obliquely downwardly from the supporting members 8 are arms 10 to the outer or lower ends of which are pivotally secured links 11. Rotatably mounted between the outer ends of links 11 is a roller 12 to which is fixed a crank handle 13 which permits of manual rotation of said roller.

Coöperating with the supporting members 8 is a U-shaped member 14, the respective ends of which are fulcrumed at 15 to the outer sides of said members 8, as clearly shown in the several views. Coöperating with the links 11 is a U-shaped member 16, 75 the respective ends of which pass loosely through perforated laterally projecting ears 17 carried by said links, as shown. The ends of the members 16 are connected with the ears 17 by means of nuts 18 and 19 which are threaded upon said ends of the member 16, helical compression springs 20 being interposed between the nuts 19 and said ears. The bights of the members 14 and 16 are 80 pivotally connected together by means of a sleeve or tube 21 loosely embracing the same, as shown.

The construction is such, as will be seen, that when the member 21 is moved forwardly and downwardly to the position 95 shown in dotted lines in Fig. 2, the roller 12 will be carried into operative relation with the roller 9 and yieldingly held in engagement therewith by reason of the tension or pressure of springs 20. Furthermore, the arrangement is such that, in this movement of the member 21, as the roller 12 reaches a position in contact with the roller 9, the levers 14 and 16 will be on dead center, that is the points 15, 17 and 21 will be positioned 100 in the same line; continued downward movement of the member 21 carrying said members 14 and 16 past the dead center position 105 against the influence of the springs 20. After the dead center position has been 110

passed, it is of course clear that, the pressure of the springs 20 will act to further move the members 14 and 16 in this direction until the same contact with a stop which will be 5 constituted by the upper edge of the pail, and thus serve to automatically hold the roller 12 in operative position. In moving said roller from operative position, the reverse operation is, of course, resorted to, 10 namely, moving the member 21 upwardly to the full line position shown in Fig. 2. The mop which it is desired to wring is placed between the rollers 9 and 12 when the latter is in inoperative position or spaced from 15 the roller 9, whereupon the member 21 is moved downwardly in order to carry said roller 12 into engagement with the mop. The handle 13 is then rotated to carry the mop head outwardly, in which operation 20 the wringing is effected, as is readily understood.

Provided at the inner sides of the members 8 are angularly positioned fingers 22 which serve to hold the mop head centrally between 25 the rollers in the wringing operation. The lower ends of the attached portions of the fingers 22 are bent inwardly, as at 23, in order to constitute stops adapted for engagement with the upper edge of the pail in 30 order to limit the downward movement of the device relative thereto.

The pail is held secure upon the ground or floor during the wringing operation by means of a member 24, the ends of which 35 are pivotally engaged with eyes 25 projecting from opposite sides of the band 1. The outer end portion or bight 26 of the member 24 constitutes a foot rest whereby the device may be held securely in position 40 against the ground through foot pressure, as will be readily understood.

While I have illustrated and described the preferred form of construction for carrying my invention into effect, this is capable of 45 variation and modification without departing from the spirit of the invention. I, therefore, do not wish to be limited to the precise details of construction set forth, but desire to avail myself of such variations and 50 modifications as come within the scope of the appended claims.

Having described my invention what I claim as new and desire to secure by Letters Patent is:

55 1. In a mop wringer, the combination with a receptacle, of a relatively stationary roller arranged at the upper end of said receptacle; a relatively movable roller arranged for movement toward and from said first mentioned roller; and a pair of 60 rockingly mounted members for moving said relatively movable roller into and out of operative relation with said relatively stationary roller and for automatically locking the 65 same in operative position, one of said mem-

bers being operatively connected with said relatively movable roller and the other being operatively connected with said relatively stationary roller, the free outer portions of said members being connected together, substantially as described. 70

2. In a mop wringer, the combination with a receptacle, of a relatively stationary roller arranged at the upper end of said receptacle; a relatively movable roller arranged for movement toward and from said first mentioned roller; and a pair of rockingly mounted members for moving said relatively movable roller into and out of operative relation with said relatively stationary roller and for automatically locking the 80 same in operative position, one of said members being operatively connected with said relatively movable roller and the other being operatively connected with said relatively stationary roller, the free outer portions of said members being connected together, said members being adapted, when said relatively movable roller is in operative position, to move into and past the dead center position, substantially as described. 85

3. In a mop wringer, the combination with a receptacle, of a relatively stationary roller arranged at the upper end of said receptacle; a relatively movable roller arranged for movement toward and from said relatively stationary roller; means for moving said relatively movable roller, said means comprising a substantially U-shaped member having its ends pivotally mounted and 100 operatively connected with said relatively movable roller; a second substantially U-shaped member having its ends pivotally mounted and operatively connected with said relatively stationary roller; and a pivotal connection between the bights of said members, substantially as described. 105

4. In a mop wringer, the combination with a receptacle, of a relatively stationary roller arranged at the upper end of said receptacle; a relatively movable roller arranged for movement toward and from said relatively stationary roller; means for moving said relatively movable roller, said means comprising a substantially U-shaped member having its ends pivotally mounted and 110 operatively connected with said relatively movable roller; a second substantially U-shaped member having its ends pivotally mounted and operatively connected with 115 said relatively stationary roller; and a pivotal connection between the bights of said members, the connected portions of said members being adapted, when said relatively movable roller is in operative position, to move into and past a plane passing through the pivotal points of the ends of said members, substantially as described. 120

5. In a mop wringer, the combination with a receptacle, of a supporting element em- 130

5 bracing said receptacle; a pair of diametric bearing members arising from said supporting element; a relatively stationary roller mounted between said bearing members; a pair of pivoted arms connected with said bearing members; a relatively movable roller mounted between the free ends of said arms and adapted, upon swinging of said arms, to move toward and from said 10 relatively movable roller; and manually operable means pivotally connected with said bearing members and said arms for moving said relatively movable roller into and out of operative relation with said relatively stationary roller and for automatically locking the same in operative position, substantially as described.

6. In a mop wringer, the combination with 20 a receptacle, of a band embracing said receptacle; a relatively stationary roller rotatably supported by said band; a relatively movable roller supported by said band so as to permit the movement of said roller toward and from said relatively stationary 25 roller; and rockingly mounted means for moving said relatively movable roller into and out of operative relation with said relatively stationary roller and for automatically locking the same in operative position, 30 substantially as described.

7. In a mop wringer, the combination with a receptacle, of an adjustable band embracing said receptacle, said band comprising a 35 body part; an end member mounted for longitudinal adjustment upon one end of said body part; a connecting element embracing said end member and the other end of said body part; and a pair of coöperating rollers supported by said band, substantially as de- 40 scribed.

8. In a mop wringer, the combination with a receptacle, of an adjustable band embracing said receptacle, said band comprising a body part; an end member mounted upon 45 one end of said body part; a slot and pin connection between said body part and said end member permitting of longitudinal adjustment of the latter upon the former; a connecting element engaging with said end member and the other end of said body 50 part; and a pair of coöperating rollers supported by said band, substantially as de- scribed.

9. In a mop wringer, the combination with 55 a receptacle, of a relatively stationary roller arranged at the upper end of said receptacle; a relatively movable roller arranged for movement toward and from said first mentioned roller; rockingly mounted 60 means for moving said relatively movable roller into and out of operative relation with said relatively stationary roller and for automatically locking the same in operative position; and springs on said last mentioned 65 means coöperating with said relatively mov-

able roller for yieldingly holding said roller in an advanced position relative thereto, substantially as described.

10. In a mop wringer, the combination with a receptacle, of a relatively stationary 70 roller arranged at the upper end of said receptacle; a relatively movable roller arranged for movement toward and from said first mentioned roller; a pair of rockingly mounted members for moving said relatively movable roller into and out of operative relation with said relatively stationary roller and for automatically locking the same in operative position, one of 75 said members being pivotally connected with said relatively movable roller and the other being pivotally connected with said relatively stationary roller, the free outer portions of said members being connected together; and springs on the actuating member coöperating with said relatively movable roller for yieldingly holding said roller in operative relation with said relatively stationary roller when said relatively movable 80 roller has been moved to operative position 90 by said member, substantially as described.

11. In a mop wringer, the combination with a receptacle, of a relatively stationary roller arranged at the upper end of said receptacle; a relatively movable roller arranged for movement toward and from said relatively stationary roller; means for moving said relatively movable roller, said means comprising a substantially U-shaped member having its ends pivotally connected with said relatively movable roller; a second substantially U-shaped member having its ends pivotally connected with said relatively stationary roller; a pivotal connection between the bights of said members, the connected portions of said members being adapted, when said relatively movable roller is in operative position, to move into and past a plane passing through the pivotal points of the ends of said members; and springs on the U-shaped actuating member coöperating with said relatively movable roller for yieldingly holding said roller in operative relation with said relatively stationary roller when said relatively movable 100 roller has been moved to operative position 105 by said members, substantially as described.

12. In a mop wringer, the combination with a receptacle, of a band clampingly embracing said receptacle adjacent the upper 110 edge thereof; inwardly projecting members on said band engaging over the upper edge of said receptacle; foot operable means engaging with said band for holding down the same; and a pair of coöperating rollers supported by said band, substantially as de- 115 scribed.

13. In a mop wringer, the combination with a receptacle, of a band clampingly embracing said receptacle adjacent the upper 120 125 edge thereof; inwardly projecting members on said band engaging over the upper edge of said receptacle; foot operable means engaging with said band for holding down the same; and a pair of coöperating rollers supported by said band, substantially as de- 130 scribed.

edge thereof; inwardly projecting members on said band engaging over the upper edge of said receptacle; a foot operable member pivotally connected with said band and adapted to rest upon the ground for holding down said band and receptacle; and a pair of coöperating rollers supported by said band, substantially as described.

Copies of this patent may be obtained for five cents each, by addressing the "Commissioner of Patents, Washington, D. C."

In testimony whereof I have signed my name to this specification in the presence of 10 two subscribing witnesses.

JAKOB SCHMOLINER.
